DESIGN FOR A STEREOSCOPIC VIEWER

Felix Gilbert, New York, N. Y., assignor to
Harold B. Shapiro, New York, N. Y.

Application October 12, 1946, Serial No. 133,901

Term of patent 14 years

(Cl. D57—1)

To all whom it may concern:

Be it known that I, Felix Gilbert, a citizen of the United States and resident of the city, county, and State of New York, have invented a new, original, and ornamental Design for Stereoscopic Viewer, of which the following is a specification, reference being had to the accompanying drawing, forming part thereof.

Fig. 1 is a top plan view of a stereoscopic viewer showing my design.

Fig. 2 is a front view thereof.

Fig. 3 is a side view thereof.

Fig. 4 is a rear view thereof.

The side not shown is similar to Fig. 3 and the bottom plan view is similar to Fig. 1, except the knurled handle is omitted.

I claim:

The ornamental design for a stereoscopic viewer, substantially as shown and described.

FELIX GILBERT.
